COLLAPSIBLE TUBE SQUEEZER

Isaiah Scott, 1279 E. 223rd St., Bronx, N.Y.

Filed Apr. 20, 1965, Ser. No. 84,877

Term of patent 7 years

(Cl. D4—3)

Fig. 1.

Fig. 2.

Fig. 3.

Fig. 4.

FIGURE 1 is a top perspective view of a collapsible tube squeezer showing my new design,

FIG. 2 is a top plan view thereof,

FIG. 3 is a side elevational view thereof,

FIG. 4 is a front elevational view thereof,

FIG. 5 is a top perspective view of a modified form thereof,

FIG. 6 is a top plan view thereof,

FIG. 7 is a side elevational view thereof, and

FIG. 8 is a front elevation view thereof.

The tube shown in broken lines in FIGS. 3 and 7 is included for illustrative purposes only.

I claim:

The ornamental design for a collapsible tube squeezer, substantially as shown and described.
